UNITED STATES PATENT OFFICE.

ARTHUR H. FRANKE, OF MANITOWOC, WISCONSIN.

PHONOGRAPH-STOP MECHANISM.

1,302,650.

Specification of Letters Patent.

Patented May 6, 1919.

Application filed August 30, 1918. Serial No. 252,101.

To all whom it may concern:

Be it known that I, ARTHUR H. FRANKE, a citizen of the United States, and resident of Manitowoc, in the county of Manitowoc 5 and State of Wisconsin, have invented certain new and useful Improvements in Phonograph-Stop Mechanism; and I do hereby declare that the following is a full, clear, and exact description thereof.

10 My invention relates to new and useful improvements in stop mechanisms for phonographs, more particularly of the disk type, and adapted to stop the playing of records of different sizes at the proper times.

15 It is in general the object of my invention to simplify and otherwise improve the structure and to increase the operative efficiency of devices of this character, a more specific object residing in the provision of a stop 20 mechanism which may be most readily applied to various types of phonograph structures now in use.

It is a further and important object of my 25 invention to avoid the necessity of manipulating the tone arm in this manner to procure setting of the stop mechanism for a pre-determined stop, and it is more particularly my object in this connection to apply a selective setting means for the stop mechanism 30 which may be operated in conjunction with certain symbols placed on the record denoting the length of time which the record is to be played, such symbols corresponding with symbols or graduations of the setting 35 means to determine its operation.

With the above and other objects and advantages in view, my invention resides more particularly in the novel construction, combination and arrangement of parts which 40 will be hereinafter described and pointed out in the appended claims.

In the accompanying drawings:

Figure 1 is a plan view of a phonograph showing my improved stop mechanism associated therewith, portions of the turn-table and record thereon being broken away to show the major portion of my mechanism which is disposed thereunder.

Fig. 2 is an enlarged plan view of the setting dial and its casing, a portion of the casing being broken away.

Referring now more particularly to the accompanying drawings, 5 designates the playing base of a phonograph cabinet on which is mounted the usual turn-table 6 carrying a record disk 7 which is engageable by the diaphragm (not shown) of the usual horizontal swinging tone arm 8.

My improved stop mechanism includes a base-plate 9 which is secured on the playing base 5 and which extends under the turn-table, having pivoted thereto under the turn-table a brake lever 10 having an actuating arm 11 extending outwardly from under the periphery of the turn-table, and having at 65 one side of this actuating arm a second arm 12 carrying a friction block 13 engageable in the conventional manner for braking action with the inner periphery of the turn-table wall. At the other side of the arm 11, inwardly of said wall, the lever is provided with a bearing surface 14, concentric to the pivotal axis of the lever, and provided with a recess 15 therein. The lever is resiliently urged to clamping position by a retractile 75 spring 16 secured thereto at its side remote from the brake block 13 and secured to the base plate. Intermediately pivoted to the base plate also at this side of the brake lever is a second lever 17 having one end 80 bent laterally and forming a pawl engageable in the recess 15 of the brake lever to hold the brake lever in retracted position against the action of its spring 16. The other end portion of the lever 17 is extended obliquely 85 of the pawl end of the lever, with one side portion bent laterally to form an elongated bearing surface 19 which lies in a plane intersecting the tone arm.

For rocking the lever 17 to releasing position at the end of a variable pre-determined playing interval, a slide bar 20 is mounted for sliding movement in a plane substantially parallel to the plane of the bearing face 19 by passage of the outer portion of 95 the lever through the walls of a casing 21 formed on that portion of the base-plate 9 which projects from the periphery of the turn-table 7. Pivoted on the end of the lever adjacent the bearing surface 19 of the lever 17 is an angular lever 22 having one end engageable against the bearing surface and

having its other end projecting outwardly of the periphery of the turn-table for engagement by a pin 23 suitably secured to and depending from the intermediate portion of the tone arm 8. Thus, as the tone-arm reaches its desired inward limit of swinging movement, it will rock the lever 22 and consequently rock the lever 17 to retracted position, permitting braking operation of the lever 10 under the influence of its spring 16, and it will be noted that the position of the lever 22 determines the amount of inward playing movement permitted the tone arm.

Different records, even of the same general size, have differing lengths of playing grooves, and for adjustably positioning the lever 22 in accordance with the different playing lengths of the records, a dial 23 is rotatably mounted in the outer portion of the casing on a knob shaft 24 which projects from the casing and which carries a conventionally shown pinion 25 meshing with a gear wheel 26 journaled in the casing under the dial and meshing in turn with a series of rack teeth 27 on the lever carrying slide bar 20. The dial carries a series of symbols 28 associated preferably with graduation marks which are viewed through a sight opening 29 in the casing, and these symbols correspond to symbols 30 placed on the record disks and denoting the playing lengths of the disks.

Thus, in the operation of my improved mechanism, the disk 23 is rotated by the knob shaft 24 to display through the sight opening 29 of the casing a symbol corresponding to the symbol of the record to be played, and thus rotation of the disk sets the rock lever 22 in proper position. Then, as the playing arm moves inwardly to its desired limit of playing movement, it engages the lever 22, rocking the lever 17 to draw its pawl end from the recess 15 of the brake lever 10, permitting braking actuation of said lever by engagement of the brake block 13 with the turn-table while under influence of the spring 16. In this movement of the brake lever 10, the pawl end of the lever 17 rides upon the bearing surface 14 of the brake lever, and consequently when the handle 10 of the brake lever is grasped to release the turn-table for the playing of another record, the pawl end of the lever 17 will be automatically engaged in the recess 15 of the brake lever to thus reset the stop mechanism, this movement of the lever 17 to resetting position being procured by a leaf spring 31 secured to the base-plate and engaging said lever at its under portion remote from its pawl end, it being noted that this resetting operation is independent of relative movement of the slide bar and the pawl 22 carried thereby which may thus be

previously set for operation at a different inward limit of movement of the tone-arm. 65

An exceedingly simple and efficient stop mechanism has thus been provided which may be most readily and accurately set in accordance with the differing playing operations. The symbols 30 of the record disks may be placed thereon during the manufacture of the disk, or they may be placed thereon by the user of previously purchased record disks, since the proper symbol for co-action with a corresponding stop mechanism symbol may be most readily determined by placing the tone arm at its inward desired limit of movement, with the pawl 22 still further inwardly, and then rotating the disk 23 to bring the pawl 22 into engagement with the depending pin 23 of the tone-arm and then noting the symbol and graduation which appears in the sight opening 29 of the casing 21.

It will be further appreciated that other 85 methods of coördinating the symbols carried by the record disk with certain positions of the rock lever 22 may be provided, and that to meet differing conditions of use, various changes and modifications of 90 structure may be employed without departing in any manner from the spirit of the invention as defined by the appended claims.

What is claimed is:

1. A phonograph stop mechanism includ- 95 ing a base member, a brake lever pivoted on the base member, a brake member carried by said lever, means urging said lever to braking position, a second lever pivoted on the base member and engageable with the first 100 lever to hold it against the action of said means, a bearing surface on the second lever, a slide bar, a trip lever carried by said slide bar and engageable with various portions of the bearing surface of the second lever 105 to move the second lever upon engagement of said trip lever by a phonograph tone-arm, means for holding the slide bar against sliding movement, and symbols associated with the slide bar for determining positions 110 of the trip lever for engagement by the phonograph tone-arm.

2. The combination with a phonograph structure including a turn table having a peripheral brake portion and mounted on said 115 base member, of a lever pivoted on the base member inwardly of the peripheral portion of the turn table, a handle carried by said lever and projecting outwardly of the turn table periphery, a brake member carried by the lever for engagement with the turn table periphery, a second intermediately pivoted lever having one end portion engageable with the first lever to hold it against movement and having an elongated bearing sur- 120 face on its other end portion disposed in a 125

plane transverse to the tone-arm, a slide arm movable in a plane substantially parallel to the normal plane of said bearing surface, a trip lever pivoted on the slide arm and engageable with said bearing surface and having a portion projecting outwardly of the turn table periphery, and a member on the tone-arm engageable with said trip lever

to rock the second lever and release the brake lever. 10

In testimony that I claim the foregoing I have hereunto set my hand at Manitowoc, in the county of Manitowoc and State of Wisconsin.

ARTHUR H. FRANKE.
